CAGE, LANDER, AND GATE COMBINATION

Glenn W. Merritt, Bowerston, Ohio, assignor to
The Mining Safety Device Company, Bowers-
ton, Ohio, a corporation of Ohio

Application November 8, 1930. Serial No. 494,305

7 Claims. (Cl. 214—126)

The present invention relates to an improved construction in the apparatus associated with the shaft of a mine for handling cars automatically and with facility, in order to speed up the delivery of mined materials, to increase the output, and to correspondingly reduce the cost of operating expenses.

This I accomplish by interlocking the cagers, gates and landers in such a manner as to be controllable by means of a single lever, and operable by means of the mine cage itself. With the foregoing mechanisms interlocked, as will hereinafter be fully described, the operator stationed at the particular level from which the loaded cars are to be brought to the surface merely actuates a lever. This action swings the landing chairs into the shaft and into operative position for receiving and supporting the cage at the selected level. The operation of the lever also moves a trip crank into position to be actuated by the cage as it is lowered onto the landing chairs, whereby the safety gates are opened and the cager or feeder is operated to allow a loaded car to enter upon the cage, pushing the empty car therefrom. When the cage is hoisted the safety gates are automatically closed, and the feeder mechanism is operated to advance the trip of cars upon the incline, in a known manner.

The primary object of my invention is to interlock the various mechanisms associated with each level in the mine, in such a way as to automatically operate the gates, the landers and the trip shaft of the feeder mechanism.

Another object of my invention is to assure that the gates of the sides of the mine shaft will remain lowered except when the cage is in loading position at a selected level, which is advantageous as contributing to the safety of the operators.

Another object is to provide a single cage operated means which will operate all of the mechanisms utilized for the purpose of loading cars onto and off of the cage, and will also open the safety gates disposed on both sides of the mine shaft.

A further object is to utilize the feeder operating shaft, which is actuated by the cage, to operate a system of levers for raising and lowering the safety gates.

Another object is to provide an apparatus of the character described which is sturdy but of comparatively simple and inexpensive construction. Further objects and advantages of my invention will appear from the detailed description.

In the drawings:

Figure 1 is a side elevational view of the car

handling and gate operating means embodying my invention;

Figure 2 is a plan sectional view taken substantially along the line 2—2 in Figure 1, showing two adjacent mine shafts;

Figure 3 is an elevational view of the gate operating mechanism, partially in section, and taken substantially along the line 3—3 of Figure 2;

Figure 4 is an end view of the car feeding mechanism as viewed from the mine shaft; and

Figure 5 is a vertical detail sectional view of the mine shaft end portion of the feeder and associated parts.

Referring now to Figure 1, the car handling equipment comprises in general, a car feeding mechanism or cager 10, a cage 11 operating within the mine shaft 12 and landers 13 which support the cage in position with the cage rails 14 in alignment with the mine rails 15. In Figure 1 the car 8 is in position upon the cage 11 and the trip of cars on the incline, indicated by car 9, is being held back by the feeder.

Of the foregoing equipment the landers 13 are manually operated, while the cager 10 and the cage 11 are, broadly, of known type. Preferably, the cage is provided with car lock or holding means such as that disclosed in my copending application filed June 21, 1930, Serial No. 462,810.

The cage in my copending application is provided with two sets of horns 16 and 17, respectively, for locking a car upon the cage. The horns 16 are automatically opened when the cage comes to rest upon the landers. The horns 17 are adapted

to be opened by the entering loaded car, which pushes the empty car from the cage. The entering car actuates means for releasing the horns 16 which close in front of such car, and horns 17 close in back of the rear wheels of the entering car thereby locking the car in place upon the cage.

This means of positioning and holding a car upon the cage is, broadly, known in the art and need not be illustrated nor described here in greater detail, it being sufficient to note that the cage is provided with suitable car locking or holding means.

The landers 13, comprise a plurality of landing chairs 18 and 19 which are secured upon supporting shafts 21 and 22 rockably mounted at opposite sides of the mine shaft 12. Crank arms 23 and 24 are suitably keyed to the shafts 21 and 22, respectively, adjacent one end thereof, and connecting links 25 and 26 are pivotally connected with the crank levers. A link structure 27 is pivotally mounted substantially centrally of the

105

110

compartment 12 at one side thereof, as shown at 28, and includes oppositely directed arms which are connected by links 25 and 26 to the free ends of arms 23 and 24, respectively. A link 29 connects one arm of the link 27 to an operating lever 31 upon a rockably mounted shaft 32. The landing chairs are normally disposed out of the path of the travel of cage 11, but when the cage is to be stopped at landing, as in Figure 1, the lever 31 is moved in the direction of arrow 33, whereby the landing chairs are brought into the position shown for supporting the cage with the rails 14 thereon in direct alignment with rails 15. Movement of lever 31 beyond the position of Figure 1, in the direction indicated, is prevented by chains 34 each having one end suitably secured to the landing chairs, the other end of each chain being anchored in a suitable manner.

It is common practice to provide a mine shaft with two or more cages, and it is for this reason that two complete car handling units have been illustrated. Since the structures of these units are the same and the operation of each is identical to the other, a description of one will suffice.

The interlocking means is best illustrated in Figures 2 and 5. A shaft 32 is pivotally mounted in suitable bearings, at right angles to rails 15 and somewhat below the same. A stub shaft 36 is disposed above shaft 32 and at right angles thereto. This stub shaft is slidably mounted for endwise movement in bearings 37 and 38. Shaft 32 is provided with a pair of arms 39 suitably secured thereto. Shaft 36 has a shiftable means connected therewith comprising a sleeve collar 41, collar 42 and a shift collar 43. The sleeve collar 41 and collar 42 are secured together and to shaft 36 by means of a pin 44, while the shift collar 43 is disposed between collars 41 and 42 in the manner best illustrated in Figure 5. The shift collar 43 is provided with laterally extending pins 45 that engage through slots 46 formed in the free ends of arms 39. The foregoing arrangement provides a means for shifting shaft 36 endwise by means of lever 31 whenever the latter is operated to throw the landing chairs into operative position.

The primary purpose of the stub shaft 36 is to operate the cager or car feeding mechanism. One end of shaft 36 is provided with a trip crank 47 which is suitably secured to the shaft and moves therewith as the latter is shifted endwise. The other end of shaft 36 is provided with a squared portion 48 which extends into socket member 49 having a square opening 51 therein to cooperate with the squared end of shaft 36. Socket member 49 is secured to the main shaft 52 of the cager by any desired fastening means such as pin 53. By this construction, rotation of shaft 36 will be imparted to the main shaft 52 of the cager through the instrumentality of the socket member 49, and furthermore, the socket member as herein constructed will allow shaft 36 to move endwise relative to shaft 52 without affecting the operative connection between said shafts. Shaft 52 is suitably supported in bearings 50 and held against endwise movement by collars 60.

Rotation of shaft 36 to operate the cager for feeding a car on to the cage is caused by means of the cage striking the trip crank 47 when the latter has been moved into the path of travel of the cage. When a car is to be loaded at a landing, the attendant moves lever 31 into the position shown in Figure 1. The landers are swung into the shaft compartment by means of the mechanism previously described. In moving lever 31, shaft 32 is simultaneously rotated, actu-

ating the shifting mechanism which moves shaft 36 endwise. As a result of this, the trip crank 47 is moved into the path of the cage to be subsequently operated thereby. As the cage is lowered, it strikes the trip crank 47, thereby operating the cager mechanism, and immediately thereafter the cage will come to rest upon the landers, at which time the car locking mechanism of the cage is also simultaneously operated. This cuts out a loaded car from the trip, and this loaded car travels down the incline and onto the cage pushing the empty car therefrom in a known manner.

In order to understand the operation of the cager and its association with the interlocking mechanism comprising the present invention, I will give a brief description thereof. Any type of automatic car feeding device may be used in connection with my invention, but I prefer to use a caging mechanism of the type best illustrated in Figures 1 and 2. This cager comprises two sets of pivotally mounted horns 54 and 55, which have limited movement along the rails. Expansion coil springs 56 abut horns 54 and 55 and cushion the movement thereof under the impact of the loaded cars. These horns are provided with suitable arms 57 whereby they may be rocked into open and closed positions. Connecting links 58, which are adjustable in length, are pivotally connected at 59 with the arms of horns 54, and at 61 with a toggle link 62. Toggle link 62 is connected to the main shaft 52 of the cager to turn therewith. Connecting links 63, of the same character as links 58, are pivotally connected to the arms of horns 55 and to the toggle link 64 which is also suitably connected to shaft 52. It is to be further noted that the toggle links 62 and 64 are so related that one set of horns will be in open position when the other set is closed to engage the wheels of a car, and vice versa.

The operation of the cager may readily be explained in connection with Figure 2, wherein two cagers have been illustrated. The cager A is shown in its normal position for holding a car in readiness to be released for passage on to the cage. A weight 65, is secured to the main operating shaft 52 of the cager and normally maintains the shaft in a position to hold the horns 54 in closed position, and horns 55 in open position. When the trip crank is moved into the path of the cage, the latter will strike it and, rotate the stub shaft, and the rotation of the stub shaft is imparted to the cage shaft through the socket member. When this occurs, the cager mechanism is operated so as to open horns 54 and close horns 55, as at B. As the cage is hoisted, the crank 47 is released and the car feeding mechanism is restored, by weight 65, to the condition shown in the cager A of Figure 2.

The foregoing description has been chiefly confined to the mechanisms for handling cars. It is common practice in mines to provide suitable gates for the entrances into the mine shaft from the various levels. This is generally so in all mines whether they have car handling equipment or not, inasmuch as gates are necessary as a safety measure to safeguard against accidents. I have provided such gates, and although they do not have a direct bearing on the car handling equipment, I have devised means whereby gates are interlocked with the car handling equipment in such a manner as to be opened automatically and closed by the operation of the car handling equipment.

Suitable gates and their associated operat-

ing mechanisms are illustrated in Figure 3. Since the two sets of gates are of like construction and have similar operating mechanisms, a description of one set will suffice. In Figure 3, gates 5 C are shown in closed position while gates D are shown in open position. Gates C are disposed on opposite sides of the mine shaft and extend across the aligned openings or entrances to the shaft and across the path of the cars which are 10 handled by either one of the two car handling units. Gates C are mounted for vertical movement in guides 70, and the latter may be of channel iron construction, as shown, or of any other desired construction. A cable 71 has one 15 end secured to a clevis 72 carried by the gate, passes up and over suitably supported pulleys 73, and has its other end secured to a ring 74. A second cable 75 is also attached to ring 74 and passes over another set of pulleys 76 to the other 20 side of the shaft where it is connected to the opposite gate. A short cable 77 is attached to ring 74 and connects with the end of arm 78 of a bell crank lever 79, at 81. The bell crank lever 79 is rockably mounted at 82, and a pull rod 83 25 has one end pivotally connected with the other arm 84 of the bell crank lever. The other end of the pull rod 83 is pivotally attached to a crank arm 85.

Referring now to Figures 3 and 5, it is seen that 30 the crank arm 85 is operatively connected with the stud shaft 36 of the cager mechanism and is rotated thereby. Since shaft 36 is shiftable, a splined connection 86 is provided between the crank arm 85 and shaft 36 as best seen in Figure 35. Since crank arm 85 is disposed adjacent bearing 37 it is held thereby against appreciable movement with stub shaft 36 toward this bearing. To prevent movement of the crank arm 85 in a direction away from bearing 37, a stop member 87 is 40 bolted to bearing 37. This may be made in the form of a flat plate having its projecting end 88 downturned and forked as at 89 to freely straddle shaft 36 adjacent the crank arm 85 in the manner best shown in Figure 5. With this construction 45 the crank arm 85 will always remain in position regardless of the endwise shifting of shaft 36, and the gate opening mechanism will not be subjected to undue side stresses or binding.

The gate opening mechanism by virtue of its 50 connection with the cager mechanism as hereinbefore described, is operated by the cage as the latter descends into the shaft and strikes trip crank 47. Furthermore, the gates on both sides of the shaft compartment are automatically 55 opened in this manner by a mechanism which is disposed at one side only of the shaft compartment. When crank arm 47 is depressed by the cage, the gates are opened quickly by the link mechanism and will remain in open position until 60 the cage is again raised. The raising of the cage causes the cager mechanism to be restored to its normal condition, and the cager mechanism allows each of the gates to close by their own weight. The weight 65 and the gates C cooperate in restoring the cager mechanism to its normal condition and, if desirable, the gates may be made heavy enough to eliminate weight 65 altogether.

It is to be understood that the interlocking mechanism of the present invention may be varied 70 in its construction and that the particular arrangement illustrated and described is only given by way of example. For this reason I do not wish to be limited to the specific construction disclosed except in so far as I may be limited by 75 the appended claims.

What I claim is:

1. In combination, a cage operating in a mine shaft, feeder mechanism for feeding a car to the cage, a gate controlling entrance to the shaft shiftable means connected with the feeder mechanism to operate the latter, a trip crank carried by said shiftable means, means for actuating said shiftable means to move said trip crank into and out of the path of the cage, and gate opening means operatively connected with said shiftable means. 80

2. In combination, a cage operating in a mine shaft, landers for supporting said cage, feeder mechanism for feeding a car to the cage, a slide- 90 able trip shaft operatively connected with said mechanism, a trip crank operatively connected with said trip shaft, and means for moving the trip shaft into and out of position to dispose the crank in the path of travel of the cage and for moving the landers into and out of operative 95 position.

3. In combination, a cage operating in a mine shaft, landers for supporting said cage, feeder mechanism for feeding a car to the cage, a pair of gates controlling entrance to the shaft, a slide- 100 able trip shaft operatively connected with said feeder mechanism, a trip crank secured to said trip shaft to move therewith, gate opening means operatively connected with the trip shaft, and manually operated control means for moving the trip shaft into and out of position to dispose the trip crank in the path of travel of the cage and for moving the landers into and out of operative 105 position.

4. In combination, a cage operating in a mine 110 shaft, landers for supporting said cage, feeder mechanism for feeding a car to the cage, a gate controlling entrance to the shaft, trip means operable by the cage for operating said feeder mechanism, means operated by said trip means 115 for opening said gates, and means for moving the trip means into and out of position to be operated by the cage and for moving the landers into and out of operative position.

5. In combination, a cage operating in a mine 120 shaft, landers for supporting said cage, feeder mechanism for feeding a car to the cage, a gate controlling entrance to the shaft, shiftable trip means operable by the cage for operating said feeder mechanism, means operated by the trip 125 means for opening said gate, an operating lever connected to the landers for moving the latter into and out of operative position, and means connecting said lever with said shiftable trip means for moving the latter into and out of the path of said cage in accordance with movement of the landers into and out of operative position. 130

6. In combination, a cage operating in a mine shaft, landers for supporting said cage, feeder mechanism for feeding a car to the cage, shiftable means operable when in one position by said cage for actuating said feeder mechanism, a control lever connected to the landers for moving them into and out of operative position, connections between said shiftable means and said 140 control lever for moving the shiftable means into and out of position to be operated by the cage, and connections between the lever and the landers for moving the latter into and out of operative position in accordance with movement 145 of the shiftable means into and out of position to be operated by the cage.

7. In combination, a cage operating in a mine shaft, a feeder for delivering loaded cars to the cage, said feeder including a trip member mov- 150

able into the path of travel of the cage to be actuated thereby and normally disposed out of the path of travel of the cage, connections between the trip member and the feeder for operating the feeder to deliver a car to the cage when said trip member is actuated by the cage, a gate controlling entrance to the shaft, landers for supporting the cage, means for moving the

landers into and out of operative position and for simultaneously moving the trip member into and out of position to be actuated by the cage, and connections between the feeder and the gate for opening the gate when the feeder is operated to deliver a car to the cage and closing the gate when the feeder is returned to normal condition. 80
